CLAIM

The ornamental design for an electric relay, as shown and described.

DESCRIPTION

The patent or application file contains at least one drawing executed in color. Copies of this patent or patent application publication with color drawing(s) will be provided by the Office upon request and payment of the necessary fee.

1. Relay, electric

1.1 : Perspective

1.2 : Front

1.3 : Back

1.4 : Left

1.5 : Right

1.6 : Top

1.7 : Bottom

1.8 : Front view, mounting direction is changed

Matter which is shown in the reproduction, but for which protection is not claimed, is indicated in the reproduction by means of yellow color; the relay may be selectively mounted horizontally or vertically; reproduction 1.8 represents a state when the relay is rotated and mounted vertically.

1 Claim, 8 Drawing Sheets
